(57) CLAIM

The ornamental design for a wheel, as shown and described.

DESCRIPTION

FIG. 1 is a front left perspective view of a wheel, showing my new design;

FIG. 2 is a front view thereof; and,

FIG. 3 is a left side view thereof; the right side being a mirror image.

The broken line in the figure drawings represents unclaimed portion of the design only and forms no part of the claim.

1 Claim, 2 Drawing Sheets

FIG. 3
